UNITED SHOE MACHINERY COMPANY, OF PATERSON, NEW JERSEY, A CORPORA-
TION OF NEW JERSEY.

SOLE FASTENING AND TRIMMING MACHINE.

1,139,727.

Specification of Letters Patent. Patented May 18, 1915.

Application filed August 7, 1912. Serial No. 713,785.

To all whom it may concern:

Be it known that I, WILLIAM T. B. ROBERTS, a subject of the King of England, residing at Leicester, Leicestershire, England, have invented certain Improvements in Sole Fastening and Trimming Machines, of which the following description, in connection with the accompanying drawings, is a specification, like reference characters on the drawings indicating like parts in the several figures.

This invention relates to machines for inserting fastenings and more particularly to fastening inserting machines which are provided with a trimming knife whereby the rough rounding operation may be performed upon the sole, particularly about the heel seat end of the sole, while the sole is being attached to the shoe.

The soles of shoes which are made at the present time are usually trimmed so that the edge is perpendicular, or approximately perpendicular, to the sole face but owing to space considerations in the usual fastening inserting machine a reciprocating knife of the ordinary rough rounding type which moves in a plane perpendicular to the sole face cannot be used, since for close trimming of the sole, particularly in the region of the heel seat, by such a construction the knife and mechanism for supporting and operating it would have to be thrown forward almost in a line with the fastening driver, and this would leave insufficient room for the shoe to be brought into position for the fastening inserting operation.

According to the present invention, which contemplates the use of a knife moving to and fro, this difficulty is obviated by the provision of an oscillating knife, and an object of the present invention is to provide an improved construction of knife supporting and operating mechanism.

In order that the oscillating knife may in its cutting stroke be approximately perpendicular to the face of the sole and yet shall have its operating mechanism well behind the driver so as to leave sufficient space for the shoe, it is advisable that the oscillations should take place about an axis which is approximately at the level of the tread face being operated upon, and that the radius of the path of travel of the knife shall be as

small as is convenient. Accordingly, in the preferred embodiment of the invention there is provided an oscillating trimming knife which enters the work from the rand or welt face of the sole and which moves in an arc about an axis that is approximately parallel to the plane of the sole that is being trimmed.

A further object of the invention is to provide knife operating mechanism which may be adapted to operate upon various classes and sizes of shoes, and accordingly in a machine having the features aforementioned there is provided means for adjusting the knife toward or from the fastening inserting mechanism.

It often happens that variation in the width of the projecting margin of the sole not only requires an adjustment of the knife in relation to the line of fastenings, but also an adjustment of the work gage both to the knife and to the line of fastenings, since the distance of the feather of the shoe from the line of fastenings varies according to the distance of the latter from the edge of the sole.

Another important feature of the invention is the provision of means for adjusting the gage toward and from the knife in a direction parallel or approximately parallel to the plane of the shoe bottom to provide the required adjustment aforementioned.

Another important feature of the invention is the provision of means for shifting the work gage toward and from its operative position to permit the easy insertion or removal of the margin of the sole between the work gage and the work abutment, the illustrated means comprising a connection between the gage and the horn lowering treadle whereby movement of the treadle to lower the horn for the insertion or removal of the work will at the same time lower the work gage.

The invention contemplates further that the work gage may be provided with means whereby it may be adjusted toward or from that portion of the machine against which the sole face abuts, so that the limit of the final position of the gage in relation to the work abutment may be varied according to the variations in thickness of the sole being operated upon. For convenience the work

gage may be formed upon a member which is arranged to act also as a guard between the knife and the work.

Other features and objects of the invention will appear from the following description when considered in connection with the accompanying drawings in which the invention is illustrated as embodied in a nailing machine of the type known as "loose nailers". It will be understood, however, that the invention is not limited to use with this type of machine nor to the particular construction described.

In the accompanying drawings,—Figure 1 is a side elevation, partly in section, of so much of a loose nailer with an attachment embodying the present invention as is necessary for the elucidation of the invention; Fig. 2 is a plan, partly in section, of the parts shown in Fig. 1, and Fig. 3 is a side sectional elevation of the knife supporting mechanism shown in Fig. 1.

Projecting from the frame of the machine in proximity to the driver 2 is a bracket 4 which is adapted to carry the knife, knife guard and shearing plate. Upon the underside of the bracket and at its outer edges are guideways 6 adapted to coöperate with corresponding guideways in a slider 8 so that the latter may be adjusted toward and from the driver, the adjustment being obtained by means of a rack 10 cut upon the underside of the bracket and a pinion 9 mounted upon a spindle journaled on the slider 8, the said spindle having on one end a handle 12 by which the operator can move it to adjust the slider toward or from the driver. The handle is held in adjusted position by means of a spring friction washer.

At opposite sides of the slider 8 are two bearing brackets 14, 16 in which is mounted a shaft 18 that lies so as to be approximately parallel to the margin of the portion of the sole that is being trimmed and that projects beyond the brackets at both ends; fulcrumed upon these ends are the extremities 20, 22 of a forked yoke 24 which straddles the slider and which carries at its middle portion a flange 26. The flange is provided with an arcuate guideway which is concentric with the fulcrum of the yoke and in which a correspondingly curved knife 28 is gripped by means of a clamping plate and screw. The forked yoke being fulcrumed upon the shaft ends will therefore move the knife in the arc of a circle whenever the shaft is oscillated. In order that the oscillation of the knife may be as smooth as possible a balance weight 30 is provided upon the yoke arm 22. It will be noted that the position of the knife is in close proximity to that of the driver so that both operate at substantially the same portion of the sole.

In order to oscillate the yoke 24 the fol-

lowing mechanism is used. Projecting from the outside of the yoke arm 22 are two lugs 32 bored to receive a pin 34, and mounted on the pin between the lugs is a rectangular block 35 having extending rearwardly from it a stub shaft 36 which is located in a bearing in a boss 38 mounted upon the end of the driving shaft 40, the stub shaft being held in its bearing by means of a plate 42 screwed to its end and fitting into a recess in the boss adjacent to the shaft. The boss 38 has a projecting rim adapted to fit into a corresponding groove upon a flange 44 upon the end of the shaft 40 and is secured to the flange by means of bolts. The bearing for the stub shaft lies at an angle to the axis of the driving shaft such that the axis of the stub shaft and the axis of the driving shaft will intersect at the center of the shaft 18. As the driving shaft rotates the stub shaft will be carried around in its bracket but will not be rotated therewith since it is held in position by means of the rectangular block from which it projects and the co-acting lugs upon the yoke arm. Consequently the lugs and the shaft 18 which is fixed to the yoke arm will be oscillated as the driving shaft 40 is rotated, and since the knife is attached to the shaft 18 the knife also will be constantly operated whenever the machine is working.

The slide 8 is provided with a forwardly projecting extension 46 which is preferably adjustable and which extends under the throat and acts as a work abutment. It has inserted in its under face a shearing plate 48 of any suitable material against the edge of which the knife 28 is adapted to work scissorwise. Thus the knife as it were shears through the projecting margin of the sole, the shearing plate of course being automatically adjusted with the knife since both are mounted upon the slider 8.

When the slider 8 is adjusted toward and from the driver the rectangular block 35 which oscillates the shaft will also be adjusted correspondingly and in order to provide for this adjustment the driving shaft is constructed in two parts. The end of one part is reduced at 52 and is provided with a spline working in a keyway in a recess in the other part which carries the pulleys by which the apparatus is operated. Consequently as the slider 8 is moved backward and forward the shaft 40 is shortened or lengthened correspondingly.

The mounting of the knife guard will now be described. Mounted in a suitable guideway upon the upper side of the bracket 4 and about its middle is a second slider 56 having teeth 58 cut upon its underside at its rearward end, these teeth engaging the teeth of a pinion 60 upon a spindle 62 mounted in the bracket 4. The spindle is provided at one end with a handle 64 by means of

which the operator can move the second slider toward and from the driver, the handle being retained in adjusted position by means of a spring friction washer 66. Carried upon the underside of this slider 56 is a shoulder on which is mounted a pin 68 carrying one end of a bracket 70 whose other end is so bent that it projects underneath the yoke and the shank of the knife 28. 5 This free end is provided with a guideway in which is bolted the correspondingly shaped shank of a guard 72 that projects upwardly and forwardly in such a manner as to form a guard between the knife and 10 the work.

At its upper end this guard 72 is shaped to abut against the welt side of the projecting margin of the sole so as to act as a sole gage to assist in positioning the sole margin 20 in relation to the work abutment and it is also shaped as an edge gage to abut against the shoe adjacent to the crease to position it in relation to the knife. Projecting from the lower side of the guard bracket 70 in a 25 lug 74 upon which a link 76 is pivoted, the link at its other end passing freely through a pivoted block upon the outer end of an arm 78 attached to the horn shaft 80. The link at its lower end carries a collar 82 so 30 that as the treadle is operated to depress the horn for the insertion of the work the block will strike the collar and will carry the link downward with it thus rocking the bracket 70 about its pivot and lowering the guard so 35 that the work may be more easily inserted between it and the work abutment.

The knife guard is normally held in its uppermost position by means of a spring 84 and this position can be adjusted by means 40 of a screw-threaded pin 86 passing through the bracket 70 and adapted to contact with a lug 88 projecting downward from the second slider 56.

Having described my invention, what I 45 claim as new and desire to secure by Letters Patent of the United States is:—

1. In a sole fastening and trimming machine, a work abutment, sole supporting means operating within the shoe and between which and the work abutment the sole to be fastened is clamped, and an oscillating sole trimming knife having its operative movement about an axis outside, approximately in the plane of, and substantially 50 parallel to the portion of the sole to be trimmed, whereby the sole cutting stroke of said knife is substantially normal to the sole, the path of travel of said knife being nearest to said work support substantially 55 at the point of operation upon the sole.

2. In a sole fastening and trimming machine, a work support, a work abutment between which and the work support the portion of the sole to be fastened is clamped 60 and an oscillating trimming knife arranged

to enter the sole from the rand side and to coöperate with said work abutment in trimming the edge of the sole and having its operative movement about an axis that is approximately in the plane of, and parallel to, 70 the portion of the sole that is being trimmed, whereby the nearest point of approach of said knife to said work support is where it cuts the sole.

3. In a sole fastening machine, a work support, a work abutment between which and the work support the portion of the sole to be fastened is clamped and an oscillating trimming knife arranged to enter the sole from the rand side and to coöperate with 75 said work abutment in trimming the edge of the sole and having its operative movement about an axis that is approximately in the plane of, and parallel to, the portion of the sole that is being trimmed, and means for 80 adjusting said knife toward and away from the shoe.

4. In a sole fastening and trimming machine, a work support, a work abutment between which and the work support the portion of the sole to be fastened is clamped and an oscillating trimming knife arranged to enter the sole from the rand side and to coöperate with 90 said work abutment in trimming the edge of the sole and having its operative movement about an axis that is approximately in the plane of, and parallel to, 95 the portion of the sole that is being trimmed, and a guard for said knife arranged to enter the rand crease between the upper and the 100 sole and to serve as a gage for the sole fastening operation and also to determine the width of the trimmed portion of the sole.

5. In a sole fastening and trimming machine, a work support, a work abutment between which and the work support the portion of the sole to be fastened is clamped and an oscillating trimming knife having its operative movement about an axis substantially in the plane of the portion of the sole 105 to be trimmed, a plate against which the bottom of the sole abuts and over the edge of which said knife is adapted to effect a shearing cut, and means for simultaneously adjusting said knife and plate to vary the 110 width of the trimmed sole margin.

6. In a sole fastening and trimming machine comprising means for inserting sole fastenings, an oscillating trimming knife having its operative movement about an axis 120 substantially in the plane of the portion of the sole to be trimmed, a guard for said knife arranged between said knife and the shoe upper and serving as a shoe gage, and means for adjusting said guard and knife 125 toward and away from the point of operation of the means for inserting sole fastenings.

7. In a sole fastening and trimming machine comprising means for inserting sole 130

fastenings, an oscillating trimming knife arranged to enter the sole from the rand side, a shearing plate coöoperating with said trimming knife and against which the bottom of the sole is adapted to abut, a guard opposed to said shearing plate and serving as a shoe gage, and means for adjusting said plate, knife and guard toward and away from the point of operation of the means for inserting sole fastenings.

8. In a sole fastening and trimming machine comprising means for inserting sole fastenings, an oscillating trimming knife, a guard for said knife serving also as a shoe gage, means for adjusting said guard and knife toward and away from the point of operation of the means for inserting sole fastenings, and means for adjusting said guard relatively to said knife.

9. In a sole fastening and trimming machine comprising means for inserting sole fastenings, an oscillating trimming knife having its operative movement about an axis substantially in the plane of the portion of the sole to be trimmed, a guard for said knife adapted to engage the shoe upper and to serve as a shoe gage, a work support, and connections between said guard and said work support whereby said guard partakes of the movement of said work support.

In testimony whereof I have signed my name to this specification in the presence of two subscribing witnesses.
